UNITED STATES PATENT OFFICE.

THEODORE A. BRENNER, OF ANTIGO, WISCONSIN.

BUILDING CONSTRUCTION.

Application filed October 4, 1923. Serial No. 666,543.

To all whom it may concern:

Be it known that I, THEODORE A. BRENNER, a citizen of the United States, and resident of Antigo, in the county of Langlade and State of Wisconsin, have invented new and useful Improvements in Building Construction, of which the following is a description, reference being had to the accompanying drawings, which are a part of this specification.

This invention relates to improvements in building construction and more particularly to siding material.

It is one of the objects of the present invention to provide means for constructing a building which will have the appearance exteriorly of being a log cabin.

A further object of the invention is to permit the use in buildings of slab portions 20 of trees which are not usually of much value.

A further object of the invention is to provide siding material formed from slabs of sawed or split trees in which the natural 25 rounding of the slab or tree is used as the face, either with or without the bark.

A further object of the invention is to provide siding of the class described which is neatly matched or ship-lapped.

30 A further object of the invention is to provide siding material which is of very simple construction, is strong and durable, is inexpensive to manufacture, and is well adapted for the purpose described.

35 With the above and other objects in view, the invention consists of the improved building construction, and its parts and combinations as set forth in the claims, and all equivalents thereof.

40 Referring now more particularly to the accompanying drawing in which the same reference characters indicate the same parts in all of the views:

Fig. 1 is a perspective view of the improved building construction or siding;

Fig. 2 is an end view thereof;

Fig. 3 is a front view thereof, showing the siding used in a vertical position;

Fig. 4 is a view similar to Fig. 2; and

50 Fig. 5 is an end view of a slightly modified form of the invention.

Referring to the drawing it will be seen that the numeral 8 indicates slabs formed from split or sawed logs or other lumber.

55 The edges of each slab are rabbeted as at 9 and the slabs are used as siding material

on a building, being positioned with their edges adjacent each other. Chink strips 10 are further provided and are positioned over the rabbeted edges to close the joints and to 60 form a tight connection with the frame of the building. Said chink strips are secured to the slabs by nails 11 which are preferably driven into the material at an angle as shown and so as to cross each other. The 65 nails pass through the chink strips, the slabs, and enter the frame of the building, thereby serving to hold the siding to the frame.

It is obvious that the siding may be 70 mounted on a building in either a horizontal or a vertical position. In Figs. 1 and 2 the siding is shown in a horizontal position, while in Fig. 3 it is illustrated in a vertical position of use. Furthermore the siding 75 may be provided with the bark peeled off, or in its natural state with the bark left on the lumber. In Fig. 5 the siding is shown with a layer of bark 12 covering the outer surface of the slabs and the chink strips. Fig. 5 also illustrates a slightly modified 80 form of the invention in which the rabbeted edges 9 are formed with overlapping tongue and groove portions 13 and 14, thereby forming a very tight joint.

85 From the foregoing it will be seen that an improved form of siding is provided which is adapted for use in construction work to give the exterior of a building the appearance of being built of logs. Also the siding 90 is of very simple and novel construction and is well adapted for the purpose described.

What I claim as my invention is:

1. Siding material including boards formed with rounded outer faces, a tongue 95 along each side of each board, said boards being positioned with their adjacent tongues in juxtaposition and a chink strip for each pair of adjacent tongues and positioned so that half of the chink strip covers each 100 tongue.

2. Siding material including boards formed with rounded outer faces and flat inner faces, a tongue along each side of each board, and a wooden chink strip formed 105 with a rounded outer face and a flat inner face for each pair of adjacent tongues and positioned on the same to cover the joint therebetween.

3. Siding material including boards of 110 plano-convex section having tongues along both edges and in the plane of the flat sur-

faces, chink strips of plano-convex section to cover each pair of adjacent tongues, and means passing through said chink strips and said tongues to secure the chink strips thereto.

4. Siding material for mounting on uprights, including boards of plano-convex section having tongues along both edges and in the plane of the flat surfaces and positioned with the tongues adjacent each other,

wooden chink strips of plano-convex section to cover each pair of adjacent tongues, and means passing through said chink strips and said tongues to secure the chink strips thereto and to hold the boards in juxtaposition, said means being arranged to enter uprights to hold the siding thereto. 15

In testimony whereof I affix my signature.

THEODORE A. BRENNER.
